UNITED STATES PATENT OFFICE

2,434,535

INTERNAL THREAD GAGE

John F. Anders, Kitchawan, N. Y.

Application September 29, 1944, Serial No. 556,362

1 Claim. (Cl. 33—178)

1

This invention relates to thread gages.

The object of the invention is to provide a quick-acting, direct-reading, uniform pressure, internal thread gage having interchangeable parts for use in threaded holes of different diameter and shape.

A preferred embodiment of the invention is illustrated in the accompanying drawing in which

Fig. 1 is a plan view of the device;

Fig. 2 is a longitudinal section thereof on the 10 line 2—2 of Fig. 1;

Fig. 3 is a front or head-on view of the head of the device;

Fig. 4 is a transverse section on the line 4—4 of Fig. 1;

Fig. 5 is a plan view of the graduated scale plate; and

Fig. 6 is a plan view, partly broken away, of the actuating shaft of the device.

The thread gage herein claimed has a two-piece housing construction, the head member 10 and the handle member 20. They are joined end to end by means of screws 11.

The head member comprises a tubular portion 12 having three radial arms 13 integral therewith, an end plate 14 which has three corresponding arms 15 and three side plates 16 which are sandwiched in between said arms 13 and 15 and to which said arms are affixed.

Toothed segments 17 and slotted segment 18 are carried in the spaces formed between each radial arm 13 and its corresponding end plate arm 15 and between the side plates 16 which said arms adjoin. Segments 17 are fixed in said spaces by means of screws 19. Segment 18 is radially movable in its space, being slidably fixed therein by means of bolt 9 which passes through its slot 8. A compression spring 7 is carried within said slot, being braced against bolt 9 and tending, thereby, to urge segment 18 inwardly.

The handle member 20 comprises a tubular member having a rectangular window 21 formed centrally thereof, said window being flanked by a pair of diametrically opposite slots 22 which are formed longitudinally of said member. A graduated scale 23 having slotted ends 24 is adjustably fixed by means of screws 25, to said handle member, longitudinally thereof, adjacent to, and paralleling said window.

A transparent sheet 26 covers said window and said scale, being raised slightly above the latter. An escutcheon 27 is screwed to the handle member by means of screws 28, holding said transparent sheet in place. The handle member is closed at its free or rear end by means of

2

axially apertured screw cap 29 whose aperture has an enlarged, threaded portion 30.

Slidably disposed in said handle and head members is a shaft 40 whose forward end has a downwardly sloping, flattened portion 41 which serves as an inclined plane, and whose rear end 42 is of hollow construction and of reduced outer circumference. A shoulder 43 is formed at the juncture between the main body of the shaft and the reduced rear end.

Transversely fixed in said shaft is a finger grip 44 which, when the shaft is disposed in said handle and head members, protrudes through slots 22. Affixed to said shaft adjacent said finger grip, and at right angles thereto, is an indicator arm 45 having an indicating finger which occupies the space between the scale 23 and its transparent covering 26. The finger is adapted to ride over, and lengthwise of, the scale, when the shaft is moved longitudinally of the head and handle members.

A compression spring 50, carried by the reduced rear end of the shaft and braced between screw cap 29 and shoulder 43, urges said shaft forward. Acting against the pressure of said spring is an air check valve 51. Said valve includes an axially apertured shaft 52 whose forward portion is disposed in the hollow rear portion 42 of the main shaft 40 and whose rear portion is enlarged and threaded to fit into the enlarged, threaded cap screw aperture 30. The axial hole or boring 53 in shaft 52 has an enlarged rear portion which accommodates a ball 54, an axially apertured, internal plug or nut 55 and a small compression spring 56 braced between said ball and said plug.

A lever of the third class 60 is pivoted to the head member 10, longitudinally thereof. It carries a centrally disposed, transverse roller 61 which is engaged by the flattened sloping portion 41 of the main shaft. Its free end 62 is ball or roller shaped, and is adapted to engage the under surface of radially movable segment 18 against the pressure of spring 7.

45 The device may be used as follows:

The finger rip is pulled back, thereby causing rearward movement of shaft 40 against the action of spring 50. This has the effect of partially disengaging the lever 60 and of permitting segment 18 to move inwardly in response to the thrust of spring 7. A further effect is the evacuation of much of the air in the hollow end 42 of the shaft, through boring 53 and the aperture in plug 55. It also has the effect of drawing air into the tubular portion 12 of the head member

through the clearances between the segments and the plates which surround them.

The device is now ready for insertion into the threaded aperture sought to be measured. The finger grip is released, thereby enabling the shaft 40 to move forward in response to the action of spring 50. Sudden forward movement is blocked, however, by the cushion of air in front of the shaft, and by the partial vacuum behind it. Only slowly is the air cushion evacuated, and the vacuum filled. Air passes into the hollow portion 42 past ball 54 which spring 56 holds against the opening of boring 53.

The result is that when shaft 40 is permitted to move forward and to engage lever 60 which in turn engages segment 18 and pushes the same outwardly against the tension of spring 7, there is always uniform pressure of the shaft upon the lever, and of the lever upon the segment.

The function of the slots in the scale 23 is to provide for adjustment thereof relative to the position of the segments and also to compensate for wear of the parts.

Different forms of the above described device may be had without departing from the principles of the invention. For example, only two instead of three segments may be used. The size of the segments may vary. Segments other than toothed or threaded segments may be used.

I claim:

An internal screw thread gage comprising a housing, two fixed and one radially movable segments radially disposed therein, the free ends of said segments being provided with teeth which are adapted to mesh with internal screw threads, a compression spring member engaging said radially movable segment and urging said segment to move inwardly, a longitudinally movable shaft longitudinally carried in said housing, and hav-

ing a gently tapered reduced forward end, a longitudinally extending arm pivoted at one end to said housing, its free opposite end engaging the inner end of said radially movable segment, said arm being provided intermediate its two ends with a transversely disposed roller which engages the tapered forward end of the shaft, a second compression spring member engaging said shaft and urging it forwardly whereby outward radial movement of the movable segment is effected against the action of the first spring member, a finger grip on the shaft whereby it may be moved rearwardly against the action of the second spring member, thereby effecting an inward radial movement of said movable segment by releasing it to the action of the first spring member, an air check valve cushioning the forward movement of the shaft effected by the action of the second spring member, a longitudinally extending graduated scale adjustably fixed on the housing and an indicator therefor fixed on the shaft.
